UNITED STATES PATENT OFFICE

LEONARD L. GILMAN, OF CINCINNATI, OHIO, ASSIGNOR TO LYRIC OPTICAL CO., OF CINCINNATI, OHIO, A CORPORATION OF OHIO

DESIGN FOR A PAIR OF SPECTACLES

Application filed February 23, 1932. Serial No. 42,963. Term of patent 14 years.

To all whom it may concern:

Be it known that I, LEONARD L. GILMAN, a citizen of the United States, residing at Cincinnati, in the county of Hamilton, and State of Ohio, have invented a new, original, and ornamental Design for a Pair of Spectacles, of which the following is a specification, reference being had to the accompanying drawing, forming a part hereof.

The figure is a front perspective view of a pair of spectacles, showing my new design.

The design consists in an unbalance between the pair of frameless or rimless lenses and the mountings, resulting from setting or connecting the mountings to the lenses along a line extremely above a horizontal line through the axes of the lenses.

I claim:

The ornamental design for a pair of spectacles as shown and described.

LEONARD L. GILMAN.
